UNITED STATES PATENT OFFICE.

HENRY L. BORSTELMAN, OF LYON MOUNTAIN, NEW YORK.

TONIC-APPLYING COMB.

Application filed December 22, 1922. Serial No. 608,471.

To all whom it may concern:

Be it known that I, HENRY L. BORSTELMAN, a citizen of Germany, residing at Lyon Mountain, in the county of Clinton and 5 State of New York, have invented certain new and useful Improvements in Tonic-Applying Combs; and I do hereby declare the following to be a full, clear, and exact description of the invention, such as will enable others skilled in the art to which it 10 pertains to make and use the same.

The invention provides a comb for applying a liquid preparation to the scalp and hair, said comb being preferably of glass 15 and adapted to be attached to a bottle containing the preparation which is applied directly to the scalp and hair from the bottle.

Other objects and advantages will be apparent and suggest themselves as the nature 20 of the invention is understood.

While the drawings illustrate an embodiment of the invention it is to be understood that in adapting the same to meet different conditions and requirements, various 25 changes in the form, proportion and minor details of construction may be resorted to without departing from the nature of the invention.

Referring to the accompanying drawings 30 forming a part of the application,

Figure 1 is a central, longitudinal section of a comb embodying the invention, showing the same attached to the neck portion of a bottle,

Figure 2 is a top view of the parts shown in Figure 1,

Figure 3 is a detail side view showing more clearly the connecting means between the comb and bottle, and

Figure 4 is a detail view of the attaching means whereby the comb is secured to the bottle.

Corresponding and like parts are referred to in the following description and designated in the several views of the drawings by like reference characters.

The numeral 1 designates a comb which is preferably constructed of glass and provided at one end with a tubular stem 2 formed with an outer flange 3 and bead 4. The back of the comb is formed with a longitudinal passage 5 which is in communication with the opening of the stem 2. The teeth 6 are hollow and in communication

with the passage 5. The comb is constructed to admit of its stem 2 being introduced into the neck of a bottle 7 containing the tonic or other liquid preparation to be applied to the scalp and hair. A washer 8 is interposed between the flange 3 and the neck 60 of the bottle to insure a close joint and prevent any waste of the preparation.

The comb is made secure when applied to the bottle by fastening means which embodies an oblong link 9 fitted about the stem 65 2 and engaging the bead 4. Short chains 10 engage opposite ends of the link 9 and extend along opposite sides of the neck of the bottle. A link 11 adjustably engages each of the short chains whereby to adapt 70 the fastening means to different sized bottles. Outwardly bowed bars 12 are disposed at opposite sides of the neck 13 of the bottle and their ends engage the links 11. The bars 12 form connecting means for the opposite links 11 and chains 10 and pivotally support levers 14. The levers 14 are outwardly bowed intermediate their ends and are resilient to yield slightly and secure the parts by a spring clamping action. The 75 upper ends of the levers 14 engage the outer bead or lip of the bottle neck 13 and the inner or lower ends engage the sides of the neck 13. When the parts are clamped, the strain upon the levers is outwardly and inwardly, thereby holding the outer ends of the levers in engagement with the lip at the outer end of the neck 13 and the inner ends of the levers against the sides of the neck 13. The bars 12 are likewise resilient to 80 assist the spring clamping action as well as to enable said bars to adapt themselves to different sized bottle necks.

What is claimed is:

1. Means for securing a comb of the character specified to the neck of a bottle, the same comprising an oblong link, short chains at opposite ends of the link, other links adjustably engaging the short chains, opposite bowed bars engaging the adjustable links, and levers pivotally mounted upon the bowed bars.

2. Means for securing a comb of the character specified to the neck of a bottle, the same comprising an oblong link, short chains at opposite ends of the link, other links having adjustable connection with the short chains, spring bowed bars engaging

the adjustable link, and spring levers pivotally mounted upon the bowed bars.

3. A device of the character specified, the same comprising a link, chains at opposite ends of the link, the terminal links of the chains adapted to adjustably engage other links of the respective chains, outwardly bowed spring bars connecting the terminal

links of the chains, and clamping levers mounted upon the bowed bars. 10

In testimony whereof I affix my signature in presence of two witnesses.

HENRY L. BORSTELMAN.

Witnesses:

JOHN K. MOFFITT,
C. E. CLINTON.
